Inventor:

Herbert A. Handy

UNITED STATES PATENT OFFICE.

HERBERT A. HANDY, OF TULSA, OKLAHOMA.

PUMP.

1,426,864.

Specification of Letters Patent. Patented Aug. 22, 1922.

Application filed March 14, 1921. Serial No. 453,556.

To all whom it may concern:

Be it known that I, HERBERT A. HANDY, a citizen of the United States, residing at Tulsa, in the county of Tulsa and State of Oklahoma, have invented a new and useful 5 Pump, which is described herein.

This invention is identical with the one for which I applied for Letters Patent on December 18, 1917, and which was allowed 10 April 1, 1918, the application bearing Serial Number 207731, and declared abandoned for non-payment of final fee.

The main object of my invention is to furnish a means of extracting water or 15 other liquid from tubular wells into which a cylinder of limited diameter only can be inserted.

The present invention is really a late development of an invention of my own of a 20 double action pump and for which I applied for Letters Patent, April 5, 1893, under Serial Number 479688.

The development consists chiefly in the attachment to the lower end of the piston 25 of a part, comprising two ports, controlled by a valve or valves and packing fitted closely to the main cylinder. Also the introduction at the lower end of the main cylinder of a port, controlled by a valve, 30 thus converting the double acting into a triple acting pump.

The entire reconstructed pump will be shown herein, the mechanism of which is 35 illustrated by the accompanying drawing which is a vertical section thereof.

The several parts of the pump may be best described by reference to the drawing wherein the main cylinder is indicated by the letters "A B" while "C D" indicates an 40 active cylinder or piston, acting reciprocally inside of the main cylinder and outside of the hollow head, "E F" and the feed pipe "G". The main cylinder "A B" is supplied at the upper end with a cap, into 45 which may be engaged the well pipe "J", and to the cap is attached a guide "K" for the piston rod "L" to which is attached the stop "M" which limits the valve "1".

The numeral 1 indicates an annular valve 50 working loosely about the piston rod and controls port 2. The top plate of the piston is perforated plentifully to form port 2. Numeral 4 indicates a port in the top, and "7" a port in the bottom plate of the hollow head "F" similar to the one at "2", and they 55 are controlled by valves "3" and "8" which

are connected by rods, four in number for more simultaneous action. At "10" and "15" is placed a packing about the feed pipe. Numeral "11" indicates a port in the lower 60 end of the piston proper, and "12" a valve working loosely about the feed pipe and controlling alternately both ports "11" and "13". Numeral "17" indicates a port in bottom of chamber "20" and is controlled 65 by valve "16" which in turn is limited by the stop "N" attached to feed pipe. Numeral "18" indicates a port and ball valve through which all water must enter the pump. Numeral "19" indicates the space 70 inside the piston between "6" and port "2" and "9" the space or chamber between "6" and port "11" while "20" indicates the chambers in the main cylinder between the packing at "14" and port "17". Numeral 75 "22" indicates an uncontrolled port or open grill in the side of the shallow chamber in which operates the valve "12", and at "p" is indicated a suction pipe which may be used if desired.

To explain the operation of the pump it will be noted that in the drawing, Fig. 1, the piston is shown in low position.

On the upward stroke of the piston valve 1 closes port "2" and, valve "3" opening, 85 chamber "19" is filled through port "4". Also valve "12", which controls both ports "11" and "13", opens downward and, valve "8" closing port "7", the water in chamber "9" is forced through port "11" and open 90 grill "22", into the main cylinder and delivered: port 13 having been closed by valve "12". Also valve "16" opening, chamber 20 is filled through port "17".

On the downward stroke of the piston, 95 valve "1" opens and, valve "3" closing, the water in chamber "19" is forced through port "2" and delivered. Also valve "8" opening downward; and valve "12" closing 100 upward, chamber "9" is filled through the feed pipe "G" and hollow head "F". Also valve "16" closes, while valve "12", doing double service, opens port "13" and closes port "11". Thus leaving the piston in position for the upward stroke when the water 105

which was previously in chamber "20" will be delivered. It will be noted that the water above piston cup "14" and the water in chamber "9" will be delivered on the upward stroke, and that the water in chamber 110 19 will be delivered on the downward stroke. Also that while the piston is in

action a continuous stream of water is moving through the feed pipe and hollow head to fill alternately chambers "9" and "19" and, that the valve "18" may only be useful when the piston is at rest. To assemble the parts the hollow head and piston may be fitted with the valves and packing about the feed pipe and the whole inserted in the cylinder.

10 Having thus described the construction and operation of my pump, what I claim is: A pump consisting of a main cylinder, having attached to its lower end, and extending partially through it, a stand pipe 15 fitted with a hollow head supplied with ports both on the upper and lower sides, said

ports being controlled by valves; said main cylinder being supplied at the lower end with a port and said port controlled by a valve, a piston working reciprocally inside 20 said main cylinder and outside said hollow head and stand pipe, and fitted closely thereto by packing; said piston supplied at the upper end with a port, said port controlled by a valve, and at the lower end 25 with two ports, with a small open chamber between, said chamber being supplied with a valve controlling said ports, and said chamber being supplied with open ports in its sides, all substantially as described.

HERBERT A. HANDY.
